[57] CLAIM

The ornamental design for a furniture base, as shown and described.

DESCRIPTION

FIG. 1 is a top plan view of a furniture base showing my new design;
 FIG. 2 is a side elevational view thereof, the other three side elevational views taken at 90°, 180° and 270° to FIG. 2 being substantially identical thereto;
 FIG. 3 is a bottom plan view thereof;
 FIG. 4 is a top plan view of an alternative embodiment of the present invention;
 FIG. 5 is a side elevational view thereof, the other three side elevational views taken at 90°, 180° and 270° to FIG. 5 being substantially identical thereto;
 FIG. 6 is a bottom plan view thereof;
 FIG. 7 is a top plan view of a further alternative embodiment of the invention;
 FIG. 8 is a side elevational view thereof, the other three side elevational views taken at 90°, 180° and 270° to FIG. 8 being substantially identical thereto;
 FIG. 9 is a bottom plan view thereof;
 FIG. 10 is a top plan view of another alternative embodiment of the present invention;
 FIG. 11 is a side elevational view thereof, the other three side elevational views taken at 90°, 180° and 270° to FIG. 11 being substantially identical thereto;
 FIG. 12 is a bottom plan view thereof;
 FIG. 13 is a top plan view of still another alternative embodiment of the present invention;
 FIG. 14 is a side elevational view thereof, the other three side elevational views taken at 90°, 180° and 270° to FIG. 14 being substantially identical thereto;
 FIG. 15 is a bottom plan view thereof.
